Hanson & Hanson

UNITED STATES PATENT OFFICE.

FRANK SOLEY, OF PHILADELPHIA, PENNSYLVANIA, ASSIGNOR TO THE YALE & TOWNE MANUFACTURING COMPANY, OF STAMFORD, CONNECTICUT, A CORPORATION OF CONNECTICUT.

COMBINATION PADLOCK.

Application filed June 11, 1926. Serial No. 115,386.

My invention relates to certain improvements in combination padlocks.

My invention can be applied to either a lock having a longitudinally movable swivel 5 shackle, or to a lock having a shackle provided with a series of notches arranged to be engaged by a bolt.

One object of the invention is to so construct the lock that it can not be jarred to 10 release the bolt.

Another object is to provide means for preventing the withdrawal of the shackle from the lock.

And a further object is to provide means 15 for locking the bolt when the dog is moved clear of the notches in the tumblers.

My invention further relates to the arrangement of the spring which acts to throw the bolt and apply tension to the tumblers; 20 and still further relates to improvements in the "click" mechanism for the knob of the lock.

In the accompanying drawings:

Fig. 1 is a face view of my improved combination padlock;

Fig. 2 is an enlarged face view, with the cap plate removed;

Fig. 3 is a sectional view on the line 3—3, Fig. 2;

Fig. 4 is a sectional view on the line 4—4, Fig. 2;

Fig. 5 is a rear view of the cap plate, showing the "click" mechanism;

Fig. 6 is a detached perspective view of 35 the bolt;

Fig. 7 is a detached perspective view of the bolt-throwing lever;

Fig. 8 is a perspective view of the dog;

Figs. 9 and 10 are views of the tumblers;

Fig. 11 is a view of one of the washers;

Fig. 12 is a detached view of the spring for throwing the bolt and holding the tumblers in position;

Fig. 13 is a perspective view of the casing 45 for the long arm of the shackle;

Fig. 14 is a view of the bottom plate;

Fig. 15 is a view of a modification of the invention; and

Fig. 16 is a view showing a long shackle 50 lock made in accordance with my invention.

1 is the casing of the lock, which is cylindrical in the present instance and consists of a back plate 2 and an integral deep

flange 3, which is rolled over as at 4 upon the cover plate 5, the cover plate having a 55 lug 6 which enters a recess 7 in the body portion.

8 is the knob of the lock having a pointer 9, and the shank of this knob extends through the cap plate 5 and is attached to 60 a notched disk 10, which forms a part of the "click" mechanism. The disk 10 has a pin 11 which is arranged to enter a slot 13 in a tumbler 12 of the lock, and is also notched at 10^a to receive a dog 41. 15 is 65 a "click" spring, bent as shown in Fig. 5 and secured to the back of the cap plate 5 by a rivet 16. The ends of the spring are coiled as shown in Fig. 5, so as to rest in the notches of the disk 10. These notches 70 correspond with the dial figures on the face of the cap plate, as shown in Fig. 1, so as to indicate to the person manipulating the lock the different divisions.

Located within the casing is a bottom 75 plate 17, which conforms to the shape of the casing as clearly shown in Figs. 3 and 14. The plate is held from turning in the casing by a lug 17^a which extends into a groove 1^a in the casing. Secured to this bottom 80 plate is a spindle 18, which is grooved at one side 19, Fig. 2. Mounted on the spindle are the several tumblers 20, which are spaced apart by washers 21. These washers 85 have projections which enter the groove 19, so as to prevent the washers turning on the spindle when the tumblers are turned.

The tumblers 20 have notches 22, and the upper tumbler 12 has a notch 14 to receive the dog. Each tumbler 20 has a projection 23 on one side and a projection 24 on the other side, so that when two or more tumblers 20 are assembled, the projections of one tumbler strike those of another tumbler, in order to bring the notches into 95 proper alignment with the dog.

25 is a bolt having a slot 26 for a securing rivet 27, which holds the bolt against the plate 17, yet allowing it to move longitudinally. The plate is slotted at 28 and 100 extending into these slots are the projections 29 of the bolt. The bolt has a portion 30 which is arranged to extend into the notch 31 of the arm 32 of the shackle 33. The portion 30 is inclined so as to allow the 105 shackle to be forced into the lock when the

bolt is projected, the end of the shackle being beveled as at 34.

The long arm 35 of the shackle extends through a casing 36 riveted to the bottom plate 17. The end of the shackle is reduced to form a shoulder 37, and secured to the casing 36 is a spring 38, which projects into the path of the shackle, so that when the shackle is raised to its full extent, as shown by dotted lines in Fig. 4, the spring will engage the shoulder 37 and prevent withdrawal of the shackle, but allowing it to turn freely. In the present instance, the spring 38 is held between the casing 36 and the bottom plate 17, the main body of the spring extending through a slot 39 in the casing, while the opposite end of the spring is bent and enters a slot 40 in the casing. Thus the spring is held firmly in position.

The dog 41 is mounted on a pivot pin 42, carried by a bolt-throwing lever 43. This lever has a projection 44 which enters a notch 45 in the bolt 25, so that when the lever is moved to an unlocking position, the bolt 25 is withdrawn. The notch 45, as shown in Fig. 2, is of a width so as to accommodate the projection 44 without considerable play, and the bolt must be withdrawn to allow the short arm of the shackle to enter the lock of the casing. In some instances, as shown in Fig. 15, the slot 45 may be elongated, which will allow the bolt to yield when the short arm of the shackle is forced into the lock of the casing.

Mounted on the spindle 18 is a spring 46, which has one or more coils and has arms 47 and 48. The arm 47 rests against the casing 36, while the arm 48 rests against the bolt, as clearly shown in Fig. 2. The coiled portion of the spring acts to yieldingly hold the tumblers up against the main tumbler of the lock, so that while the tumblers can be turned through the medium of the knob 8, they will retain their position on the spindle.

In place of the coil spring just described, two springs may be used. A coil spring 46^a may be located on the spindle and act to frictionally hold the tumblers in position, and a separate spring 48^a may be secured to an extension of the casing 36 and bear against a projection 25^a on the bolt, so as to yieldingly hold the bolt in the projected position, which is clearly shown in Fig. 15 of the drawings.

A dog 41, which is mounted on a pin 42, is pressed against the tumblers by a spring 49 which is mounted on the pin 42, one arm bearing against the projecting portion of the dog, and the other arm bearing against a lug 50 on the lever 43.

Bent from the bottom plate 17 is a stop 51, which is engaged by the portion 52 of the dog when the dog is out of the notch.

This prevents the movement of the bolt when the bolt is in a locked position. This stop also prevents the withdrawal of the dog from the notches when the locking lever 43 is turned, as this movement brings the dog 70 directly in front of the stop 51.

The operation is as follows:—When the mechanism is in a locking position, the knob 8 is turned, using the proper combination, until all of the notches in the tumblers are 75 in line with the dog, when the latter will be forced by its spring 49 into the notches. Then, on continuing to turn the knob in the proper direction, the lever 43 will withdraw the bolt from engagement with the nose of 80 the shackle and release the latter, which can be moved longitudinally, and when the nose of the shackle is clear of the casing, the shackle can be turned, the spring-stop 38 limiting the withdrawal of the long arm of 85 the shackle. When the mechanism is to be moved into locking position, the shackle is forced into the lock and engaged by the bolt. The disk which is attached to the knob forces the dog out of engagement with 90 the tumblers. On continuing to move the knob the tumblers are distributed and the lock is in a locked position, and when in this position the dog is turned, so that the bolt cannot be forcibly withdrawn. 95

On the cover plate 5 is a dial having a series of numerals thereon as shown in Fig. 1. The rivet 16 for the click spring extends through the cover plate and has a projecting head preferably located at the mark 60 100 of the dial. This head of the rivet acts as a finder when the lock is manipulated in the dark.

When an elongated notched shackle is used, as shown in Fig. 16, then the casing is 105 perforated at top and bottom for the passage of the shackle. The bolt can engage any one of a series of notches in the shackle, and the spring 38 acts as a stop to prevent the insertion of the shackle in the reverse 110 direction.

I claim:—

1. In a combination padlock, the combination of a casing; a cap plate secured to the casing; a shackle; a bolt engaging the 115 shackle; a spindle; tumblers mounted on the spindle; and a single spring encircling the spindle and acting in a dual capacity, first as a means of holding the tumblers in position, and, second, as a means for throwing the bolt. 120

2. The combination in a padlock, of a casing; a bottom plate mounted in the casing; a spindle secured to the bottom plate; a shackle casing secured to said plate at one 125 side of the spindle; a shackle having a long arm and a short arm, the long arm extending into the shackle casing and having a shoulder at its inner end; and a spring extending into the shackle casing and arranged 130

to engage the shoulder when the shackle is moved to withdraw its short arm from the casing.

3. The combination of a casing; a spindle; 5 tumblers mounted on the spindle; a bolt; a shackle arranged to be engaged by the bolt; a bolt-throwing lever engaging the bolt; a dog carried by the bolt-throwing lever arranged to be engaged by the tumblers; a 10 shackle casing, the shackle having a long arm and a short arm, the long arm of the shackle extending into the casing; and means within the casing to prevent the withdrawal of the shackle when the shackle is 15 released from the control of the bolt.

4. The combination in a padlock, of a casing; a shackle; a bolt engaging one arm of the shackle; a spindle; a bolt-throwing lever mounted on the spindle; a dog pivotally 20 mounted on the bolt-throwing lever; tumblers mounted on the spindle and arranged to be engaged by the dog; and a stop for limiting the movement of the dog and its lever when the dog is out of the notches of 25 the tumblers, preventing the withdrawal of the bolt from its locked position.

5. The combination in a lock, of a casing;

a spindle; tumblers mounted on the spindle; a bolt; a bolt-throwing lever for actuating the bolt; a dog; a cover plate; a knob on the 30 cover plate; a ratchet disk mounted on the inside of the cover plate and attached to the knob; and a spring secured to the cover plate and having two arms engaging the notched disk so as to produce a click when the knob 35 is turned.

6. The combination in a lock, of a casing; a spindle; tumblers on the spindle; a bolt; means for actuating the bolt; a cover plate having a dial thereon; a knob for operating 40 the actuating means; a click spring engaging the knob extension on the inner side of the cover plate; and a rivet for holding the spring in position, the head of the rivet projecting above the dial and acting as a 45 finder.

7. The combination in a lock, of a casing; a bottom plate located in the casing and having a lug at its periphery, the casing being grooved to receive the lug; a spindle secured 50 to the bottom plate; and a bolt adapted to a guide slot in the plate.

FRANK SOLEY.
